UNITED STATES PATENT OFFICE.

THOMAS A. HUTSELL, OF SPOKANE, WASHINGTON, ASSIGNOR TO HUTSELL MOTOR COMPANY, OF SPOKANE, WASHINGTON.

PISTON.

Application filed December 7, 1923. Serial No. 679,223.

To all whom it may concern:

Be it known that I, THOMAS A. HUTSELL, a citizen of the United States, residing at Spokane, in Spokane County, and State 5 of Washington, have invented certain new and useful Improvements in Pistons, of which the following is a specification.

My present invention relates to improvements in pistons for internal combustion engines and especially to that type of engines embodying a two cycle operation in which the pump and motor cylinders and tandem pistons have differential areas with the cylinders arranged in pairs and communicating, whereby one cylinder and piston form a pump for compressing and transferring a fresh charge of combustible fuel gas to the adjacent parallel motor cylinder of the engine. The cylinders and 10 pistons of each engine are co-axial and usually perpendicular to the crank shaft.

The invention may be said to reside in the novel construction of the piston in which an annular compression space or 15 chamber is provided in combination with the complementary cylinder; in the arrangement of inlet and outlet ports of the motor piston; and in the special formation of the pump piston in combination with the motor piston.

By these combinations of parts compactly arranged means are provided for compressing and transferring a fuel charge; the walls of the motor piston are cooled from 20 the interior of the piston, and by exchange of heat with the piston walls the fuel mixture or charge is heated as desired and in proportion to the amount of heat generated in the engine due to combustion at any 25 and various loads.

In the accompanying drawings I have 30 illustrated one complete example of the physical embodiment of my invention wherein the parts are combined and arranged in accordance with the best mode I have thus far devised for the practical application of the principles of my invention.

Figure 1 is a view in elevation of a co- 35 axial or tandem piston constructed according to my invention, part being broken away for convenience of illustration.

Figure 2 is a vertical central sectional view at line 2—2 of Figure 1.

Figure 3 is an enlarged detail vertical 40 sectional view at the bottom of the motor

piston to disclose the special construction therein.

The tandem piston is made up of an integral two-part member of which the pump piston 1 is of cylindrical shape open 60 at top and bottom as seen in Figure 2, and provided with exterior packing rings 2 and 3 of usual or standard type. Within the pump piston is arranged an annular, intermediate, horizontal flange 4 integral with 65 the piston wall, and beneath the flange the bearing 5 for the piston stem is located, the stem being coupled thereto as usual.

The co-axial motor piston 6 is also of 70 cylindrical construction, rising from the flange 4, but is of reduced diameter and of greater length than the pump piston 1. Between the exterior face of the motor piston and the interior face of the pump piston an annular space or chamber 7 is fashioned in which the fuel charge is compressed by an upward stroke of the pump piston when the engine is operating, and the usual packing rings 8 are carried in the 75 exterior face of the walls of the motor piston 6.

A special and meritorious construction is 80 provided for the bottom of the motor piston in the form of a sheet metal disk 9, circular 85 in shape and conforming to the interior of the cylindrical motor piston. The disk is inserted into the lower end of the motor piston and then sprung into place by inserting its edges in an annular groove 10 in the inner face of the piston wall, the groove being beveled slightly on its upper wall to facilitate entrance of the disk edges. The pressure from gases for combustion passing 90 through the motor piston will readily be resisted and their escape prevented by the 95 bottom as thus attached.

At its upper end the motor piston is closed by its integral head 11, and an exterior baffle wall 12 is fashioned on the head for 100 guiding the fresh charge into the combustion chamber and for maintaining the exhaust gases separate from the inlet of fresh fuel.

It will be noted in Figs. 2 and 3 that the 105 bottom 9 of the motor piston is arranged at an angle to the longitudinal axis of the piston and that the bottom declines toward one side of the piston. At this lower side of the bottom and in the extreme lower end of the motor piston wall I arrange a series of 110

vertically extending or longitudinal slots 13 forming intake ports for fuel gas as it is compressed in the compression chamber 7. A second series of slots 14 are provided in the wall of the motor piston above the inlet ports and approximately midway the height of the motor piston, for use as outlet ports from which the fuel gas is conveyed to the combustion chamber of an adjoining cylinder for ignition.

The charge of gas which is compressed in the chamber 7 on the upstroke of the piston is thus forced through the inlet ports 13 to the interior of the motor piston and the currents striking the opposite side of the piston walls is deflected upward toward the top or head 11 of the piston providing a turbulent movement of the gas within the piston. This circulation of the gas within the piston permits an exchange of heat from the head and walls of the piston to the contained gas, resulting in cooling the piston and heating the fuel gas. The fuel gas thus heated then passes out through the outlet ports 14, when they register with complementary ports in the cylinder of the piston 6, and then pass through a passage to the combustion chamber of the adjoining parallel cylinder.

As the inclined bottom 9 of the motor piston, as seen in Figures 2 and 3, at its lowest point, is complementary to the lower walls of the inlet ports 7, it will be apparent that any deposits from the interior of the piston 6 falling to the bottom 9 will be in the path of the incoming fuel gas currents. Such deposits will be picked up and intermingled

with fuel gas, remaining in suspension with the fuel mixture, and eventually pass toward the combustion chamber of the engine. In this manner an automatic means is provided for priming the engine at its start of operation after standing, and this arrangement of the ports with relation to the bottom of the piston prevents flooding at any time.

Having thus fully described my invention, what I claim as new and desire to secure by Letters Patent is—

1. The combination with the integral co-axial pump and motor pistons of differential areas forming an annular compression chamber, of a closed head for the motor piston, a separate bottom for the motor piston and means for securing the bottom in the piston, said motor piston having a lower inlet port from the compression chamber and an upper outlet port.

2. The combination with the co-axial pump and motor pistons, of a closed head for the motor piston, said motor piston having an interior annular groove, and a bottom member for said piston seated in said groove.

3. The combination with the co-axial pump and motor pistons, of a closed head for the motor piston, said motor piston having spaced lower inlet ports and upper outlet ports and a laterally declining annular groove in the interior wall of the motor piston, and a bottom member for said piston seated in said groove with its lowest portion adjacent the inlet ports.

In testimony whereof I affix my signature.

THOMAS A. HUTSELL.
